UNITED STATES PATENT OFFICE

2,681,024

BUTTONHOLE ATTACHMENT TO SEWING MACHINES

William Deitch, West Haven, Conn.

Application October 1, 1953, Serial No. 383,523

5 Claims. (Cl. 112—68)

1

This invention relates to sewing machinery, and in particular it relates to means associated with a sewing machine for restraining operation of button-hole slitting mechanism upon breakage of the button-hole sewing thread.

In the making of button-holes in fabrics by well-known forms of button-hole sewing machines, it is customary to stitch the eventual button-hole first and thereafter to slit the fabric within the loop of button-hole stitching by means of a cutter for the purpose of finishing the button-hole.

It has been found in the making of button-holes in this manner that while the sewing thread will frequently break the operation of the mechanism will nevertheless continue to the end of its predetermined cycle, at which time the fabric will be slit by the automatically operable cutter to form the opening in the button-hole stitching which has not been completed due to the broken sewing thread. In such cases, it has been found extremely difficult, if not impossible, to finish the button-hole stitching in a satisfactory manner because the threads of the fabric, having already been severed by the cutter, do not coact in a normal manner with the threads of the button-hole sewing machine and do not receive or support the stitching properly.

The above noted conditions have heretofore been given serious consideration and means have been provided for preventing completion of the cycle and operation of the cutter at the end of the button-hole stitching cycle in the event of sewing thread breakage at any stage in the button-hole sewing operation.

Examples of the contributions of various means for overcoming the above noted conditions are to be found in the previously granted patents to L. J. Schaeffer, No. 1,025,650; B. M. Krell, No. 1,101,746 and W. T. Leonard, No. 2,645,190, all of which, in common with the present invention, are concerned with the restraining of movement of a connecting lever from its normal inoperative position to its operative position at the end of a button-hole sewing cycle.

A primary object of this invention, therefore, is to provide marked simplification of the mechanisms disclosed in the aforesaid patents with equally effective results.

A further object of the invention is to provide simple means for preventing operation of the cutter in a button-hole sewing machine, which means is adapted for ready mounting on the sewing machine frame and which has continuous connection with the cutter operating mechanism.

2

Other objects and advantages of the invention will become apparent in the course of the following detailed description taken in connection with the accompanying drawings, wherein

Figure 1 is a fragmentary side elevational view of a standard button-hole sewing machine, with the present invention in operative association therewith; and

Figure 2 is an isometric view of the invention.

Referring now in detail to the drawings, and first to Figure 1, wherein is illustrated only such structure as is necessary to an understanding of the present invention, a portion of a standard button-hole sewing machine is indicated at 10.

15 The forwardly extending arm 11 of the machine is provided with a head 12 which houses the needle bar 13 and its driving mechanism. The top rear portion 14 of the arm 11 houses the needle reciprocating mechanism and part of a 20 stitch control mechanism not essential to an understanding of the present invention, for controlling certain steps in the stitching process known as "barring" whereby the ends of the button-hole are finished with a bar stitch.

25 The stitching thread T is stored in an un-winder rack (not shown) or any conventional reel and it extends downwardly through an aperture in the top of a thread leader post 15. The thread emerges from the post and passes through a tension device 16 provided with the usual co-operating discs. The tension device 16 is controlled by a rod 17, the purpose of which is not directly concerned with the present invention.

30 From the tension device 16, the thread extends over a thread guide 18 and from there to a tension device 19. From the tension device 19, the thread T leads to a spring take-up 20 and thence through an eye in a take-up lever 21 and from there into a slot in the face plate of the head 12. The thread then extends to the eye of the needle 22.

35 The needle 22 cooperates with a work piece which is moved by a work piece clamping device 23. The said device 23 executes a path which is suitable for stitching the laterally opposed sides and the ends of a button-hole. Since this specific form of work piece clamping device and its function is not directly concerned with the present invention, it will not be further described.

40 In the formation of button-holes by machines of the character shown and disclosed in the patents above referred to, the work piece is cut or slit within the stitched loop after the sewing operation, and to effect such cutting a knife 24 is provided which is clamped in a knife holder

25. The holder is mounted at the lower end of a vertically disposed bar 26. A downward cutting thrust is imparted to the bar 26 by a knife-bar driving lever 27 which is pivoted intermediate its ends on a hinge screw 28 which is received in a tapped hole in the arm 11. The forward end of the lever 27 is connected to the bar 26 by means of a link within the head 12 (not shown).

A spring 29 is provided, as is conventional, for biasing the lever 27 counter-clockwise with a resulting normal elevated position of the cutting knife 24. At the completion of a button-hole sewing cycle, a driving stroke is imparted to the lever 27 by a driving lever 30 through an intervening connecting link 31.

The link 31 is provided with a slot 32 which receives a screw stud 33 carried by the adjacent end of the lever 27. The link 31 is pivotally connected to the lever 30 by a pivot screw 34. The slot 32 in the link 31 provides a lost motion connection between the levers 27 and 30 and is inoperative to effect operation of the button-hole cutting knife 24.

A latch lever 35 is pivotally connected to the link 31 by means of a pivot screw 36. The lever 30 is pivotally connected to the frame of the machine by means of a screw 37 and the free outer end of the lever is provided with an elongated slot 38 in which is operatively disposed a driving roller 39 which is carried by a part of the sewing machine stop mechanism, as is conventional. The latch lever 35 is provided with a shoulder 40 which is engageable with the screw stud 33 for effecting unison operation of the levers 30 and 27 in order to effect a cutting operation by the knife 24.

An arm 41 extending rearwardly from the latch lever 35 normally rests on a tongue 42 which extends upwardly from a lever catch 43. The catch is pivotally mounted at the end of a fixed bracket 44 by means of a pivot screw bolt 45 and a cooperating nut 46. The catch 43 is provided with a follower 47 which is yieldably maintained in the path of a cam 48 on the feed shaft 49.

The latch lever 35 is normally urged into its drive lever connecting position by means of a spring 50 but is not rendered operative unless or until the tongue 42 is moved out of the path of the arm 41, which normally is effected near the end of a button-hole sewing operation.

While it is believed that sufficient button-hole sewing machine structure has been described to offer a clear understanding of the present invention, it is essential only that it be understood that during substantially the entire button-hole sewing cycle, the levers 27 and 30 are uncoupled, and that for only a short period of time at the end of the cycle the said levers are coupled together, whereby cutting operation of the knife is held ready during the time that the work clamp is positioned beneath same.

The present invention comprises an attachment for the standard button-hole sewing machine of the general character above described, and which is adapted to retain the latch lever 35 in its inoperative position as shown in Figure 1 upon breakage of the sewing thread, even though the lever has been automatically released by the tongue 42.

The improved attachment comprises a flat piece 55 having suitable means for the removable attachment of same to the frame of the sewing machine 10. The plate is provided with a forward extension 56 which is provided with an aperture

57 for reception of an extension on the thread guide 18. The plate is further provided with an aperture 58 for the reception of a securing means which may be the pivot screw 28 for the lever 27 as is indicated in Figure 1. The plate may, of course, be provided with additional securing means receiving apertures. A bar 59 is supported on the plate for horizontal sliding movement which may be effected by a bracket 60 which is pivotally secured to the plate by pin 60a, and through which bracket the bar 59 is freely slideable as is indicated in Figure 2. The rear end of the bar 59 is provided with an aperture 61 (Figure 2) for the removable reception of a pivot member 62 (Figure 1) for connection of the bar with the latch lever 35. The bar is bent at right angles intermediate its ends in the formation of a generally vertically projecting arm 63 disposed adjacent the front edge of the plate 55.

A lever arm 64 is disposed above the bar 59 in generally parallel relation thereto, and is pivotally connected to the plate as at 65. The arm 64 projects substantially beyond the front edge of the plate 55 and is bent at right angles in the formation of an arm portion 66 extending at right angles to the plane of plate 55, which angled portion adjacent its free end supports a thread guide which, as shown, is preferably in the form of a wire loop 67 having a vertical shank 67' adjustably supported in the arm portion 66 as by a set screw 68. The arm 64 is provided with a suitably positioned downwardly extending pawl or lug 69 having a forward vertical face 70 engageable with the rear face of the upper end of arm 63 upon breakage of the thread as will hereinafter be described. Adjacent the rear end of arm 64, I provide an inwardly directed stop pin 72 which extends into an arcuate slot or trackway 74 in plate 55, slot 74 being of such length as to limit the upward movement of the arm portion 66 during operation of the sewing machine, in order that the disengagement of the knife 24 be not delayed.

With the device which is the subject of this invention, operatively secured to the button-hole sewing machine as shown in Figure 1, the sewing thread T intermediate the spring take-up 20 and the main take-up 21, will extend through the loop 67 and will exert an upward pull thereon as indicated by the arrow in Figure 2. This upward pull on the loop 67 will result in the forward end of the lever arm 64 being swung upwardly about the pivot 65, whereby the lug 69 will be disposed above and spaced from the upper free end of the upper end of the vertical arm 63 of the bar 59, whereby the latter is free to move rearwardly with the latch lever 35 for a button-hole cutting operation in a normal stitching cycle wherein the sewing thread remains intact throughout such cycle.

In other words, the button-hole cutting mechanism will be free to operate in its usual manner unless the sewing thread should break during a button-hole stitching cycle. In the event the sewing thread does break during a stitching cycle, the arm 64 which is normally maintained in elevated position by the tension in the sewing thread T, will drop to the dot-and-dash position shown in Figure 1, whereupon the face 70 on lug 69 will engage the rear face of the vertical arm 63 and thereby prevent rearward movement of the bar 59 in the direction of the arrow in Figure 2 and, consequently, the latch lever will remain in its inoperative position whereby the cutter mechanism will not function even though

the entire cycle has been traversed by the needle. The spring 50 which normally functions to urge the latch lever 35 into operative position will also move the bar 59 when unconstrained by the lug 69. Should the spring 50 normally utilized on button-hole sewing machines be too weak to move the bar 59 with the latch lever 35, a stronger spring may be substituted therefor.

From the above disclosure, it is to be observed that the attachment as shown in Figure 2 is of very simple construction, and is adapted for ready attachment to the frames of existing button-hole sewing machines. It is to be particularly noted that the bar 59 has a pivotal connection with the latch lever and is bodily movable therewith, whereby relatively complex mechanism for effecting connection and disconnection of a restraining member with and from the latch lever is avoided.

While I have disclosed my invention in accordance with a single specific structural embodiment thereof, such is to be considered as illustrative only, and not restrictive, the scope of the invention being defined in the sub-joined claims.

I claim:

1. An attachment for operative connection with the frame of a button-hole stitching machine including a thread carrying needle, a button-hole cutter, a cutter operating lever, a power operated lever, a lost-motion connection between the levers, and a latch lever spring urged into interlocking connection of the levers and normally retained in retractive inoperative position during a stitching cycle by a cam controlled member, the said attachment comprising a plate, a bar slidably supported by the plate and having one end thereof connected to said latch lever, an arm pivotally connected adjacent one end thereof to the plate, said arm being provided with sew-

ing thread engageable means whereby the arm is urged upwardly by the normal tension in the thread, and normally spaced means on the bar and arm adapted to be brought into engagement upon lowering of the arm by gravity in the event of breakage of the thread for preventing movement of the bar whereby the said latch lever is restrained against movement into operative position for effecting a button-hole cutting operation.

5 10 15 20 25

2. The structure according to claim 1, wherein said plate is provided with a bracket in which said bar is supported for longitudinal movement, and said connection between the bar and latch lever comprises a pivot.

3. The structure according to claim 1, wherein said plate is of generally rectangular form and is provided with an extension having an aperture therein for loosely receiving a projection on the sewing machine frame and said plate being provided with a second aperture for receiving a securing screw engageable within the said frame.

4. The structure according to claim 1, wherein said sewing thread engageable means comprises a vertically disposed wire loop having a shank adjustably secured in said arm.

5. The structure according to claim 1, wherein said normally spaced means comprises a vertical arm on said bar having an upper free end disposed below said pivoted arm, and a lug on the lower face of said pivoted arm having a forward vertical face engageable with the rear face of said vertical arm.
